UNITED STATES PATENT OFFICE.

CHARLES A. WOOLSEY, OF MINNEAPOLIS, MINNESOTA.

MILK CRATE.

Application filed December 5, 1921, Serial No. 519,944. Renewed May 5, 1931.

The object of this invention is to provide a milk crate designed particularly for bottles of small size, such as pints, and made of strong, durable material, of such construction that it is capable of withstanding the rough handling to which crates of this kind are ordinarily subjected.

A further object is to provide a crate having all the necessary elements of durability but at the same time comparatively simple and inexpensive to manufacture.

The invention consists generally in various constructions and combinations, all as hereinafter described and particularly pointed out in the claims.

In the accompanying drawings forming part of this specification,

Figure 1 is a perspective view of a milk crate embodying my invention,

Figure 2 is a plan view of the same,

Figure 3 is a sectional view on the line 3—3 of Figure 2.

In the drawing, 2 represents the lower end rails or slats and 3 the corresponding side rails or slats of the crate. Intermediate side and top slats 4 and 5 are provided and a top slat 6 is shown separated by a space 7 from the lower slats 2 to allow room for the insertion of the hand in moving the crate. This opening for the insertion of the hand also allows the circulation of air through the crate and around the bottles therein when the crates are stacked one upon another. Reinforcing corners 8 are provided by means of which the side and end slats are rigidly secured together. Groups of rods 9 are mounted in the slats 2 and reinforcing rods 10 connect the opposite slats 3 and cooperate with the rods 9 to support the bottles in the crate. Bars 11, preferably of wood, extend lengthwise of the crate, spaced a suitable distance apart to allow the insertion of the bottle between them, and straps 12 and 12^a preferably flat straps of metal are arranged above and below these bars at right angles substantially thereto and are secured to the bars by suitable means, such as rivets 13, which, as shown in Figure 3, extend vertically through the bars and through the straps and are headed at each end so that the straps and bars are firmly clamped together. A sufficient space is provided between the top and the bottom slats at the sides of the crate and the intermediate one to allow the insertion of the ends of the straps and provide room for the heads on

the ends of the rivets, so that the straps are not only firmly clamped to the dividing partition bars 11 but are also securely anchored in the side walls of the crate.

The middle bar 11 is preferably beveled, as at 14, to provide room for the insertion of the fingers through the gap 7 and beneath the rail 8. When these parts are all assembled and secured together, a milk crate is provided having any desired number of pockets, twenty being shown in this case, in which small bottles of milk may be placed and safely transported from place to place.

I claim as my invention:

1. A crate comprising side and end walls composed of slats placed edge to edge, partition bars dividing the interior of said crate and cross straps co-operating with said bars and secured thereto and forming therewith a series of vertical pockets, the ends of said straps being inserted into gaps between adjacent slats of opposite walls, and rivets passing through one of the slats of said opposite walls and the straps seated thereon and securing them together, and means beneath said bars for supporting the bottles in said pockets.

2. In combination, with a milk crate having side and end walls, a series of comparatively wide bars arranged in parallel relation and dividing the interior of said crate, and a series of flat metal straps seated on the upper and lower edges of said bars and having their ends anchored in the walls of said crate, means passing vertically through said bars and the straps seated thereon and securing them together, said bars and straps dividing the interior of the crate into a series of pockets adapted to receive milk bottles.

3. A bottle crate comprising side and end walls and rods mounted in said walls in the bottom of the crate and on which the bottles are placed, bars arranged in parallel relation and dividing the space above said rods, and straps mounted on said bars transversely and seated against the upper and lower edges thereof and co-operating therewith to form a series of bottle receiving pockets, the ends of said straps projecting into said side walls, means passing through sections of said walls and through said strap ends seated therein and securing them together, and similar means passing through said bars and the straps seated thereon.

4. A bottle crate comprising side and end

walls composed of slats placed edge to edge, and means at the corners for securing the abutting slats together, the middle portions of slats intermediate the top and bottom of 5 opposite vertical walls of the crate being removed to provide openings through said walls, comparatively wide bars arranged in parallel relation within said crate between the openings in said walls, straps arranged 10 transversely of said bars and seated on the upper and lower edges thereof and secured thereto and having their ends anchored in the opposite walls of said crate, said bars and straps forming bottle-receiving pockets, means bridging the space beneath said 15 pockets within said crate and forming supports for the bottles in said pockets, the openings in said crate walls providing for ventilation when the crates are stacked one 20 upon the other, and also permitting the insertion of the hands for convenience in grasping the upper slats of the walls of said crate.

5. In combination with a crate having side 25 and end walls, a series of comparatively wide bars arranged in parallel relation and dividing the interior of said crate, and a series of straps seated on the upper and lower portions of said bars and having their ends anchored in the walls of said crate, rivets passing 30 vertically through said bars and straps and securing them together, said bars and straps dividing the interior of the crate into a series of pockets adapted to receive bottles.

35 6. A bottle crate comprising side and end walls, a series of comparatively wide bars arranged in parallel relation and dividing the interior of said crate, a series of straps seated on the upper portions of said bars and 40 having their ends anchored in the walls of said crate, means passing vertically through said bars and straps and securing them together, said bars and straps dividing the in-

terior of the crate into a series of pockets adapted to receive bottles. 45

7. A crate comprising side and end walls, bars arranged in parallel relation therein, cross members having their wider surfaces seated flatwise upon the edges of said bars transversely thereof and secured together, 50 the ends of said cross members being seated in the walls of said crate, said bars and cross members forming a series of vertical pockets, and means beneath said pockets forming a support for the articles therein. 55

8. A crate comprising side and end walls, bars arranged in parallel relation therein, cross members having their wider surfaces seated upon the edges of said bars and secured thereto, the ends of said cross members being secured together in the walls of 60 said crate.

9. A container comprising side and end walls, partition bars dividing the interior of 65 said container and cross straps having their wider surfaces engaging the upper and lower portions of said bars and secured together in the plane of said bars and cooperating with said bars to form a series of vertical pockets, and means beneath said bars for 70 supporting articles such as bottles in said pockets.

10. A container comprising side and end walls, a series of comparatively wide bars arranged in parallel relation and dividing the 75 interior of said container, and a series of flat straps having their wider surfaces seated flatwise against the upper and lower portions of said bars and secured together and having their ends anchored in the walls of 80 said container, said bars and straps dividing the interior of the container into a series of pockets adapted to receive bottles.

In witness whereof, I have hereunto set my hand this 30th day of November, 1921.

CHARLES A. WOOLSEY.
